UNITED STATES PATENT OFFICE.

PHILIP DANA CIRCUTT, OF BOSTON, MASSACHUSETTS.

CONTROLLING MEANS FOR ELEVATORS AND THE LIKE.

Application filed September 25, 1926. Serial No. 137,714.

This invention relates especially, although not exclusively, to controlling mechanism for electric elevators whereby the elevator car can be conveniently and automatically stopped at 5 points accurately positioned with respect to the several floor stations.

Electric elevators as usually installed are provided with manually operated controllers for the motor or motors, which controllers are 10 selectively movable into a variety of positions to cause the elevator car to be raised or lowered at a variety of speeds. In approaching a floor station at which the car is to be stopped, the controller is usually first moved to check 15 the speed of the car and an attempt then made to throw it into the "off" position at exactly the proper moment to bring the car to rest with its floor in accurate alignment with the floor of the station. To accomplish this with 20 any degree of accuracy requires considerable skill, and more or less jockeying is usually required in order to bring the car into even approximately the desired position.

The present invention, in its preferred 25 form, contemplates the provision, in conjunction with a manually operated controller of the type referred to, of auxiliary circuit controlling means which, as the car approaches the floor station at which a stop is to be made, 30 may be manually set to cause automatically, first, a progressive checking or reduction of the speed of the car and a subsequent stopping of the same in accurately positioned relation to the floor station.

The foregoing and other objects of the invention, together with means whereby the latter may be carried into effect, will best be understood from the following description of a preferred form thereof illustrated in the 40 accompanying drawings. It will be understood, however, that the construction, arrangement, and application shown and described have been chosen for purposes of exemplification merely, and that the invention, 45 as defined by the claims hereunto appended, may be otherwise embodied without departure from the spirit and scope thereof.

In said drawings:

Fig. 1 is a diagrammatic vertical sectional 50 view of an elevator well and an elevator car therein, showing the contact devices through which the automatic control is effected.

Fig. 2 is an enlarged plan view, partly in 55 section, of one of the contacts carried by the car and associated parts.

Fig. 3 is a side elevation of said contact

and a portion of the cooperating stationary contact.

Fig. 4 is an elevation of the adjusting means for the car contact as viewed from the 60 interior of the car.

Fig. 5 is an elevation, with the casing and a part of the controller handle in section, of the controller, the parts being in "off" position and set for manual control. 65

Fig. 6 is a section taken substantially on the line 6—6, Fig. 5.

Fig. 7 is a view similar to Fig. 5 showing the parts in an "on" position and set for automatic control. 70

Fig. 8 is a wiring diagram, the circuits employed in connection with the present invention being shown in full lines, and the remainder of the circuits, forming part of the usual manual control, being shown in broken 75 lines.

In Fig. 1 is shown an elevator well A having a plurality of floor stations B¹, B², B³, etc., and in which is suspended an elevator car C having a manually operated controller 80 D. Except as hereinafter pointed out, these parts may all be of any usual construction and are represented only diagrammatically, certain other associated parts, such as the elevator guides, being omitted entirely. The 85 electric actuating means for the elevator car may be of any approved type, and in Fig. 8 there are indicated for this purpose two electric motors E and F adapted respectively to cause upward and downward travel of the 90 car C. The controller D, as is usual in such devices, is shown in Figs. 5 to 8 as including a casing G in which is pivotally mounted a manually operated controller handle H carrying a contact I which, as said handle is moved 95 on its pivot, is brought selectively into engagement with two arcuate series of fixed contacts J¹, J², J³, and K¹, K², K³, and an intermediate insulating block L, said series of contacts being disposed concentric with the 100 pivotal axis of the handle. In the arrangement shown in Fig. 8, current is supplied, under the control of a main cut-out switch N, from any suitable source M with one terminal of which is connected a conductor O having 105 two branches O¹ and O² leading respectively to the motors E and F. From the motor E leads a conductor P having a plurality of branches P¹, P², P³, connected respectively with the contacts J¹, J², J³, and including resistance elements Q¹, Q², Q³, adapted to 110 interpose resistances of different magnitudes.

Fig. 3 is a side elevation of said contact

Similarly a conductor R leads from the motor F and has a plurality of branches R¹, R², R³ leading to the contacts K¹, K², K³ and including resistance elements S¹, S², S³ similar to those included in the conductor P. The purpose and function of the two groups of resistance elements will be fully understood by those skilled in the art. As the controller handle H is moved toward the right, of Fig. 10 8, the contact I carried thereby engages the contacts K¹, K² and K³ successively, dependent upon the speed at which the car is to be operated, these contacts being a part of the conductor R which includes the resistance elements S¹, S² and S³ for each of the contacts. The resistance of the element S¹ is greater than that of the element S² and, therefore, the car runs at a slower speed when the contacts I and K¹ are together than when the 15 contact I engages the contact K². The speed of the car is further increased as the handle is moved to bring the contacts I and K³ together by reason of the fact that the resistance element S³ in the circuit leading to the contact K³ is smaller than the preceding resistance elements. It is, of course, desirable to start the car gradually and this is accomplished by the use of the progressively decreasing resistance connected with the contacts K¹, K² and K³, respectively. This is true of the up circuit including the resistance elements Q¹, Q² and Q³ which are adapted to interpose resistances of different magnitudes, as previously explained. The contact I on the controller handle H is electrically connected, as hereinafter further described, with a conductor T leading through the switch N to the other terminal of the source M. In the arrangement shown, when the controller handle 40 H is in a position to bring the contact I into engagement with one of the contacts of the series J¹, J², etc., the car C will be moved upwardly by the motor E at a speed determined by the contact engaged; when said contact I is in engagement with one of the contacts K¹, K², etc., said car will be moved downwardly under the control of the motor F; and when the controller handle is in the position shown in Figs. 5 and 6, the contact I engages the insulating section L and the car 45 is at rest.

Except as hereinafter pointed out, the electric actuating means, manual controlling means, and connections may be of any usual type and arrangement well known in the art, form no portion of the present invention, and require no further description.

In accordance with a preferred embodiment of the present invention, there are arranged, adjacent the well A and parallel to the fixed path of movement of the car C, two elongated fixed contact members or rails U¹ and U² which are engaged by cooperating contact members V¹ and V² carried by the 60 car throughout the range of travel of the lat-

ter. Each of the contact rails U¹ and U² is made up of a series of individual contacts or rail sections 15^a, 15^b, and 15^c suitably insulated from one another as indicated at 16, the sections 15^a and 15^c being separated from one another by slightly elongated insulating sections 16^a which are engaged by the contacts V¹ and V² when the car C is in a position to bring its floor accurately in position with respect to the floor stations B¹, B², etc., 75 as indicated in broken lines in Fig. 1. The sections 15^b are preferably of less length than the sections 15^a, and the sections 15^c of less length than the sections 15^b, the sections 15^b being interposed between the sections 15^a and 15^c, and the latter being separated from the sections 15^a by the insulating sections 16^a, thus providing a plurality of zones of progressively increasing resistance to gradually check the movement of the car as 80 it approaches a floor station. In the construction shown, and as hereinafter described, the contact rail U¹ controls the car during the upward movement of the latter, and the contact rail U² controls said car during its 85 downward movement, the sections 15^a, 15^b and 15^c being arranged in ascending order in the rail U¹ and in descending order in the rail U². The contacts or rail sections 15^a, 15^b, 15^c of the rail U¹ are connected respectively by conductors 17^a, 17^b, 17^c with the conductor P, said conductors having interposed therein resistance elements 18^a, 18^b, 18^c respectively, the element 18^c being of such a character as to interpose a greater resistance 90 than the element 18^b, and the latter being such as to interpose a greater resistance than the element 18^a. Similarly, the contacts or sections 15^a, 15^b, 15^c of the rail U² are connected with the conductor R by conductors 19^a, 19^b, 19^c having resistance elements 95 20^a, 20^b, 20^c.

As most clearly shown in Figs. 2, 3 and 4, each of the contacts V¹ and V² comprises a roller 21 engaging the cooperating contact rail U¹ or U², said roller being carried by a fork or yoke 22 mounted to slide in a socket 23 with an interposed spring 24 by which said roller is yieldingly pressed against said rail. The socket 23 forms part of a clamp adjustably secured to a suitable support, herein shown as the side wall 25 of the car. As shown, the socket 23 has a stem 26 which extends through a vertical slot 27 in the wall 25 and has a threaded end to receive a combined clamping nut and handle 28. Mounted on the stem 26 at opposite sides of the wall 25 are two clamping members 29 and 30, the former being engaged by the nut 28 and the latter engaging a collar 31 on said stem. The 110 clamping member 29 preferably carries a pointer or indicator 32 which cooperates with a fixed scale 33 on the wall 25. It will be seen that, by releasing the clamp, the roller 21 may be adjusted vertically in order that 115

it may engage the insulating section 16^a when the car is accurately positioned with respect to the corresponding floor station.

In addition to the contacts J¹, J², etc., and K¹, K², etc., the controller D is provided with a pair of elongated arcuate contacts W¹ and W² disposed concentric with the arcuate series J¹, J², etc., and K¹, K², etc., and separated by an insulating section X. The contact W¹ is connected by a conductor 34 with the contact V¹, and contact W² is connected by a conductor 35 with the contact V². Cooperating with the contacts W¹ and W² is a contact 36 carried by the controller handle H and electrical- 15 ly connected, as by a suitable conductor 37, with another contact 38 also carried by said handle. Likewise the contact I is connected by a suitable conductor 39 with a contact 40 similar to the contact 38. Cooperating with the contacts 38 and 40, and adapted to be brought alternatively into engagement with either, is a manually movable contact 41 electrically connected with the conductor T. As 20 shown in Figs. 5 and 7, the contact 41 is carried by a button or plunger 42 mounted to slide in the outer end of the controller handle H, said button being normally held by a spring 43 in position to bring the contact 41 into engagement with the contact 40, but being manually depressible to move said contact 41 out of engagement with the contact 40 and into engagement with the contact 38.

In operation, when the button 42 is in its normal position, as shown in Figs. 5 and 6, the controller handle H may be moved to close the circuit to the motor E or F through the contacts J¹, J², etc., or K¹, K², etc., to cause the elevator to move upwardly or downwardly respectively at varying speeds, or to 35 stop the same by bringing said controller handle into its central or "off" position with the contact I in engagement with the insulating section L. In order to cause the car to stop automatically at any floor station and in 40 accurately positioned relation thereto, the operator, after the car has passed the preceding floor station, depresses the button 42, as shown in Figs. 7 and 8, thereby breaking the circuit to the motor E or F (depending upon 45 the direction of movement of the car) through the contact 40 and closing it through the contact 38. Thus, assuming the direction of movement of the car to be upward, as indicated by the arrow in Fig. 8, the controller 50 handle H may be in the position shown in said figure, the circuit to the motor E being then closed through the conductor T, contact 41, contact 38, conductor 37, contact 36, contact W¹, conductor 34, contact V¹, rail section 15^a, 55 15^b, or 15^c, and conductor 17^a, 17^b or 17^c, depending upon the position of the car. It will be understood that when the parts are in the 60 position in which they are shown in Fig. 8, the circuit is completed through the motor E to the source of current M through the me-

dium of the conductors 34, P, O¹ and O, rather than through the branches P¹, P² or P³ dependent upon which of the contacts J¹, J² or J³ are engaged by the contact I, and through the resistance elements Q¹, Q² and Q³, all of which are included in the conductor P leading to the motor E, when the button 42 is in the position in which it is shown in Fig. 5 with the movable contact 41 in engagement with the fixed contact 38. When 70 the controller handle H is moved to the right with the contact 36 engaging the contact W², the button 42 being depressed, the circuit from and to the source of current M is completed through the switch N, conductor T, 75 contact 41, contact 38, conductor 37, contact 36, contact W², conductor 35 to the contact V² carried by the car and thence to the motor F through any of the branches 19^a, 19^b or 19^c and their corresponding resistance elements 80 20^a et cetera, dependent upon which of the contact section 15^a, 15^b or 15^c the contact V² is in engagement with, and through the conductors R, O², O and switch N, permitting the descent of the car. The depression of the 85 button 42 preferably takes place while the contact V¹ is in engagement with the contact or rail section 15^a. Thereafter, as the contact V¹ passes from the contact 15^a to the contact 15^b, the speed of the car will be lessened 90 by reason of the increased resistance 18^b. As the contact V¹ reaches the contact 15^c, the speed of the car is further checked by reason of the further increased resistance 18^c, and when said contact V¹ reaches the insulating 95 section 16^a the circuit is broken and the car stopped. Should the position of the car when stopped be slightly above or below the desired position, the contact V¹ may, with the assistance of the indicator 32 and scale 33, be adjusted a corresponding amount to correct the 100 error. Similar adjustments of the contacts V¹ and V² may be made from time to time as required by climatic or other conditions which may affect the speed with which the 105 usual stopping brake (not shown) operates on the car supporting cable 45.

It will be understood that, after the car has been automatically stopped, as above described, the button 42 may be released, thereby again placing the car under manual control and permitting starting thereof in the usual manner.

Having thus described my invention, I claim:

1. The combination with an elevator well having floor stations, an elevator car movable in said well, and actuating means for causing said car to travel in said well, of means automatically controlled by the position of said car for controlling said actuating means including resistance arranged in zones adjacent each station to reduce the speed of the car a predetermined amount in each zone as it approaches a station.

2. The combination with a car movable in a fixed path and actuating means for causing said car to travel in said path, of manually set means automatically controlled by the position of said car for controlling said actuating means including varied resistance to progressively reduce the speed of the car at different points of its travel.
3. The combination with a car and electric actuating means therefor, of a circuit for supplying current to said actuating means, a controller for said circuit including a plurality of fixed contacts and a manually operated member having a contact selectively movable into engagement with said fixed contacts, another circuit for supplying current to said actuating means and including a fixed contact and a cooperating movable contact carried by said manually operated member, and manually set means on said member for alternatively closing said circuits.
4. The combination with a car movable in a fixed path and electric actuating means for causing said car to travel in said path, of a circuit for supplying current to said actuating means, a controller for said circuit including a plurality of fixed contacts and a manually operated member having a contact selectively movable into engagement with said fixed contacts, other circuits for supplying current to said actuating means automatically controlled by the position of said car to vary the speed of the latter at different points in its travel, said last named circuits including a fixed contact and a cooperating movable contact carried by said manually operated member, and manually set means on said member for alternatively closing said first named circuit or said last named circuits.
5. In a circuit controller for electric elevators and the like, in combination, a series of fixed contacts, a controller handle, a contact carried by said handle and selectively movable thereby into engagement with said fixed contacts, another elongated fixed contact, a second contact carried by said handle and engaging said elongated contact, a pair of contacts carried by said handle and connected respectively with said other contacts carried thereby, and a contact movably mounted on said handle and alternatively engageable with the contacts of said pair.
6. The combination with a car movable in a fixed path to and from floor stations and electric actuating means for causing said car to travel in said path, of means for supplying current to said actuating means including circuits selectively closed in accordance with the position of said car to vary the speed of the latter at different points of its travel, said circuits including a contact carried by the car and a series of resistance zones arranged in groups parallel to said path adjacent said stations and successively engaged by said first named contact to reduce the speed of the car a predetermined amount in each zone.
7. The combination with a car movable in a fixed path and electric actuating means for causing said car to travel in said path, of means for supplying current to said actuating means including circuits selectively closed in accordance with the position of said car to vary the speed of the latter at different points of its travel said circuits including a contact carried by the car and adjustable thereon in the direction of movement of the latter and a series of contacts arranged parallel to said path and successively engaged by said first named contacts.
8. The combination with an elevator car and electric actuating means for raising and lowering the same, of circuits for controlling said actuating means and including fixed contacts disposed adjacent the path of movement of said car, an interposed insulating section, a contact carried by the car and adapted to travel over said fixed contacts and insulating section, a support on the car upon which said last named contact is mounted for adjustment in the direction of travel of the car, and a scale for indicating the adjustment of said contact.
9. The combination with a car movable in a fixed path and electric actuating means for causing said car to travel in said path, of means for supplying current to said actuating means including circuits selectively closed in accordance with the position of said car, said circuits including a contact carried by the car and a series of contacts arranged parallel to said path and successively engaged by said first named contact, the circuits closed through the several contacts of said series being arranged to cause operation of said car by said actuating means at progressively decreasing speeds.
10. The combination with a car movable in a fixed path and electric actuating means for causing said car to travel in said path, of means for supplying current to said actuating means including an elongated contact member disposed parallel to the path of movement of the car comprising a plurality of zones of progressively increasing resistance to reduce the speed of the car a predetermined amount in each zone, and a cooperating contact member carried by the car, said elongated contact member being interrupted by an insulating section to break the circuit and automatically stop the car at a predetermined point.
11. The combination with an elevator well having floor stations, an elevator car movable in said well, and electric actuating means for causing said car to travel in said well, of means for supplying current to said actuating means including an elongated contact mem-

- ber disposed parallel to said well comprising a series of resistance zones adjacent each floor station and a cooperating contact member carried by the car, said elongated contact member being also provided with an insulating section to break the circuit and automatically stop the car at a floor station subsequent to the progressive reduction of speed of the car by the resistance zones.
- 10 12. The combination with a car movable in a fixed path and electric actuating means for causing said car to travel in said path, of means for supplying current to said actuating means including circuits selectively closed in accordance with the position of the car to check the speed of the latter and thereafter stop the same at a predetermined point, said circuits including a contact carried by the car and a fixed contact rail arranged parallel to said path and comprising a series of contacts providing zones of resistance of increasing magnitudes and an insulating section successively engaged by said first named contact, the circuits closed through the several contacts of said rail being arranged to cause operation of said car by said actuating means at progressively decreasing speeds as said insulating section is approached.
- 15 In testimony whereof I affix my signature.

PHILIP DANA ORCUTT.
